WELL PIPE ELEVATOR

Chester A. Lundeen, Los Angeles, Calif., assignor
to Byron Jackson Co., Vernon, Calif., a corpora-
tion of Delaware

Application April 6, 1945, Serial No. 586,888

1 Claim. (Cl. 294—90)

1 This invention relates to well pipe elevators such as are used for handling drill pipe, well casing and tubing, and relates particularly to improvements in elevators of the so-called "center latch" type.

The term "center latch" is applied to elevators of the type comprising a pair of substantially symmetrical sections having semi-cylindrical mating recesses which cooperate to define a pipe-receiving recess, the two sections being pivotally connected together at the rear side of the pipe recess and having cooperating latch means at the front side, each section having a supporting ear for supporting the elevator by a pair of links. The supporting ears are so located that the points of supporting engagement by the links lie in a transverse plane passing through the center of the pipe recess and extending substantially perpendicular to a plane through the pivotal axis and the center of the pipe recess. Because of this construction, the ears are spread farther apart as the elevator sections are swung outwardly about their pivotal connection, thus moving the lower ends of the elevator links outwardly from their normal suspended positions. The tendency of the links to return to their normal suspended positions exerts a force on the elevator sections urging them in closing direction, and thus it is necessary to make some provision for retaining the elevator sections in open position as the elevator is raised or lowered in the derrick preparatory to being latched onto a stand of pipe.

It has been customary to tilt the forward side of the elevator downwardly in order to cause the weight of the elevator to exert a spreading force on the sections in opposition to the closing force exerted by the links, and thus maintain the elevator open. This practice is, however, subject to the objection that it becomes necessary for the operator to raise the forward side of the elevator when applying it to the pipe.

It is a principal object of this invention to provide improved means for releasably retaining the sections of a well pipe elevator in open position.

It is a further object of this invention to provide simple, rugged and dependable means acting between the sections of an elevator to exert a force of predetermined magnitude holding the sections in open position, this force being only sufficient to prevent inadvertent closing of the sections by vibration or jarring, and being rendered ineffective upon initial closing movement of the sections by the operator.

A still further object of this invention is to

2 provide elevator spreading means so constructed and arranged as to be protected against damage resulting from rough handling while in use or in transit or storage.

The manner in which the foregoing and other objects are attained will be apparent from the following detailed description of a preferred embodiment of the invention, reference being had to the accompanying drawing wherein:

10 Fig. 1 is a top plan view of an elevator in closed position and embodying the invention, with parts broken away substantially in the plane of section line III—III of Fig. 6 to disclose the spreading means;

15 Fig. 2 is a view similar to Fig. 1 but showing the elevator releasably latched in open position;

Fig. 3 is a fragmentary view on an enlarged scale, taken substantially on line III—III of Fig. 6, with the elevator sections in closed position;

20 Fig. 4 is a view similar to Fig. 3 but showing the sections latched in open position;

Fig. 5 is a vertical section taken on line V—V of Fig. 3; and

25 Fig. 6 is a vertical section taken on line VI—VI of Fig. 1.

Referring to the drawing, the invention is depicted therein as applied to a center latch elevator constructed substantially in accordance with the disclosure of my Patent No. 2,257,120,

30 dated September 30, 1941, for Well pipe support. The elevator comprises generally a pair of sections **1** and **2** provided with semi-circular bores **3** and **4** which cooperate to define a circular pipe recess. The sections are pivotally connected by

35 a hinge pin **5** engaging upper and lower hinge lugs **6** and **6'** on the section **1** and hinge lug **7** on the section **2** at the rear side of the pipe recess. Latch means, generally designated **8**, is provided for releasably latching the sections together about a pipe. Reference may be had to

40 my aforementioned Patent No. 2,257,120 for a detailed description of the latch means. Supporting ears **9** and **10** project laterally from the respective sections, and are so disposed as to be

45 engaged by the usual elevator links at points lying in a transverse vertical plane extending through the center of the pipe recess. As shown in Fig. 6, each ear comprises an upper lug **11** and a lower lug **12**, the outer ends of which are connected by a block **13** (Figs. 1 and 2) to retain the link in the recess between the lugs.

Referring now to my improved spreading means, it will be observed that the lower lug **12** of the supporting ear on the right-hand elevator section **2** is recessed to provide a chamber for a

forked frame 15 which is pivotally mounted on the lug 12 on a pivot pin 16 for limited oscillation about a vertical axis. A roller 17 is journaled on a pin 18 extending between the forks of the frame 15, and has rolling contact with a cam lug 19 formed integrally with the lower hinge lug 6' of the elevator section 1. The frame 15 is constantly urged in a clockwise direction about the axis of the pin 16 by a compression spring 20, to maintain the roller 17 in engagement with the cam lug 19 and to yieldingly resist counterclockwise movement of the roller and forked frame when the roller engages a cam surface 21 at the end of the cam lug (see Fig. 4).

Referring particularly to Figs. 3 and 4 of the drawing, it will be observed that the peripheral surface of the cam lug 19 is concentric with the hinge pin 5, and consequently as the roller 17 moves along this surface of the lug during opening and closing movements of the elevator sections, the position of the forked frame 15 does not change and the force exerted by the spring 20 remains constant. However, when the elevator sections are spread apart to the relative positions shown in Figs. 2 and 4, the roller 17 leaves the peripheral surface of the cam lug and rides inwardly along the cam surface 21 under the influence of the spring 20. In order to permit the elevator sections to be swung inwardly from this position, the roller 17 and its supporting frame 15 must be forced outwardly away from the axis of the hinge pin 5 by the cam surface 21, against the force of the spring 20. The sections are thus releasably latched in open position. By varying the shape of the cam surface 21 and by selecting a spring of suitable compressive strength, the force required to be exerted by the operator on the manipulating handles of the elevator, to cause the cam surface to retract the roller and permit closing of the elevator sections, may be varied at will. It will be apparent that after the roller has been retracted and engages the peripheral surface of the cam lug, the force exerted by the spring 20 is no longer effective to restrain the sections against closing movement.

It should be noted that the operative parts of the spreading latch are fully housed within the recess in the lug 12, and are thus protected against damage by accidental blows. The parts are few

in number, and are sufficiently rugged and free from excessive wear so that they may be relied on to operate properly during the entire useful life of the elevator.

It will be apparent that various changes may be made in the construction and the arrangement of parts without departing from the spirit of the invention or the scope of the appended claim.

I claim:

In a well pipe elevator, a pair of pipe encircling members, means pivotally interconnecting said members for relative swinging movement into open and closed positions, a U-shaped frame pivotally mounted on one of said members, a roller journaled between the legs of said frame, resilient means urging said frame about its pivot to move said roller toward the axis of pivotal connection between said members and acting on said frame in line with said roller, said frame, roller, and resilient means being within the boundaries of and protected by said member, a cam on the other of said members comprising a portion concentric to the pivot axis of said members and a portion extending in a direction having its major component radial to said axis, said latter portion being engageable with said roller when said members are in open position to yieldingly retain said members in open position, said latter portion of said cam being disposed and arranged to force said roller away from said axis against the action of said spring means upon application of a force of predetermined magnitude to said members in closing direction.
